UNITED STATES PATENT OFFICE.

MICHAEL McCANN, OF GLENMORRIS, LONG ISLAND, NEW YORK, ASSIGNOR TO FRED-
ERICK OSANN COMPANY, OF NEW YORK, N. Y., A CORPORATION OF NEW YORK.

LOOPER HEAD FOR BUTTONHOLE-SEWING MACHINES.

Application filed May 31, 1922. Serial No. 564,708.

To all whom it may concern:

Be it known that I, MICHAEL McCANN, a citizen of the United States of America, residing in Glenmorris, Long Island, in the 5 county of Queens and State of New York, have invented certain new and useful Improvements in Looper Heads for Button-hole-Sewing Machines, of which the following is a true and exact description, reference being had to the accompanying drawings, which form a part thereof.

My invention is designed for use in connection with button hole sewing machines embodying two needles and two co-acting 15 loopers. In such machines as heretofore constructed trouble has been met with owing to a tendency of the loops, during the recession of the needles and immediately before the entry of the loopers into the loops, to 20 bulge out into the paths of the wrong loopers and one object of my invention is to provide a simple and efficient device for preventing this and guiding the loops, so to speak, in the paths of their proper loopers. 25 Another source of trouble in such machines arises from the liability of the needles to be pulled or pushed to one side of their proper path of travel so that they will not cooperate accurately with the loopers, and another 30 object of my invention is to provide in connection with the looper carrying head guides which will prevent harmful deflection of the needles from their proper paths of travel.

35 My invention consists first in a looper carrying head having two loopers and provided with a loop guiding plate extending between the loopers and so disposed with reference to the needles and the path travelled by the needles, that the plate will at the critical time when the loopers are entering the loops thrown off by the recession of the needles, guide the loops into the paths of the loopers, and, secondly, my invention 40 consists in so forming the looper carrying head as to form thereon guide abutments which will prevent the needles from deflection from their proper path and proper co-operative alignment with the loopers.

45 The nature of my invention will be best understood as described in connection with the drawings in which it is illustrated and in which—

50 Figure 1 is a view showing the needles and loopers in the relative positions they

occupy about the time when the needles are in their lower position, the looper head being shown as equipped with my new loop guiding plate and needle guiding abutments.

Figure 2 is a similar view showing the 60 parts in the position they occupy after the needles have moved a short distance upward and the loopers have moved forward into the loops thrown by the needles.

Figure 3 is a similar view showing the 65 needles fully retracted and the loopers in their most advanced position.

Figure 4 is a similar view of the parts in the position in which the needles are entering the loops left open by the retraction of 70 the loopers.

Figure 5 is a side elevation of the looper head and attached parts, and

Figure 6, a perspective view showing the 75 loop guiding plate and the means by which it is attached to the looper head as shown in the other figures of the drawing.

A is the needle bar to which are attached the two needles indicated at B and B'. C is the top plate of the machine in which is 80 formed the opening C' for the passage of the needles. D, the work holding plate and E the clamp for holding the work indicated at F. G, indicated in Figs. 1 to 4, is a finger which I have found it convenient to use 85 in guiding the loops into position but it forms no part of my present invention. H is the looper shaft to which is attached the looper head I which is clamped on the shaft 90 by the screws indicated at I', I', and in 95 which are secured the rods J, J, which rods are clamped in the head by set screws J² and have formed on their ends the loopers indicated at J'. The front of the looper head I is slotted as shown at I² so as to leave room 100 for the passage of the needles through this part of the head and provide abutting shoulders I³ I³ which will lie close to the paths normally travelled by the needles and will prevent the needles from being deflected 105 laterally from their proper paths during the periods when the needles extend into the slot I². The edges of the abutments I³ should be rounded as shown at I⁴. i², Fig. 5, indicates the bottom of slot I². K is the 110 loop guiding plate which, as shown, is formed on a plate K' which rests on the top face of the looper head and is held in position by the screws I'. The proper shape and disposition of the loop guiding plate K

with reference to the loopers J' and slot I^2 is best shown in Fig. 5. L , L , indicate the two threads carried by the needles and at L' , Fig. 2, I have illustrated the loops thrown off by the needles during their upward movement and at L^2 , L^2 , Fig. 4, I have illustrated the loops being cast off by the loopers during their retracting movement.

In operation as the needles pass upward 10 from the position shown in Fig. 1 towards that shown in Fig. 2, loops, as indicated at L' , are formed by the slackened threads and these loops or bulges of the thread are liable to be formed on both sides of the needles and 15 may, unless prevented, extend into the paths of the wrong loopers. In my construction, however, the loop guiding plate K prevents the inward bulging of the thread and obviates any danger of the thread being engaged by the wrong looper. It will also be 20 obvious that the plate K , as is clearly shown in Fig. 4, would prevent any inward bulging of the loops formed during the recession of the loopers and obviate any danger of a 25 loop being engaged by the wrong needle. This, however, is not so important a function as that previously described as there is not apt to be much bulging of the threads at this point in the operation of the needles 30 and loopers.

It will also be obvious that as the needles move downward to engage the thread loops on the loopers and as the loopers move into

the loops of the thread above the needle eyes, any deflection of a needle from its proper path is liable to result in the needle striking a looper or the looper striking a needle and this danger is avoided by the guiding abutments I^3 which prevent the needles being pushed or pulled into the path 40 of the loopers.

Having now described my invention, what I claim as new and desire to secure by Letters Patent, is:

1. A looper head for a button hole sewing machine having two loopers and a loop separating plate attached to and moving with the head, lying midway between the loopers and shaped to extend between and well in front of and above the looper points. 45

2. A looper head for a button hole sewing machine formed with a broad slot through which two needles work and the sides of which slot form needle guiding abutments to prevent the outward deflection of the needles into the path of the loopers, said head having two loopers secured to it with their points more closely spaced than the distance between the walls of the slot and said head having also secured to it a loop separating plate located above and midway between the walls of the slot and formed to extend between the loopers and well in front of and above the looper points. 55

MICHAEL McCANN.
